UNITED STATES PATENT OFFICE

2,132,569

BENDING BRAKE

Thomas J. Kelleher, Chicago, Ill.

Application March 22, 1937, Serial No. 132,427

2 Claims.

(Cl. 153—5)

My invention relates to bending brakes, and more particularly to the portions thereof immediately in engagement or contact with the work, and my main object is to provide an installation of elements in the work-holding and forming zones which permits the renewal or re-conditioning of these elements with facility after they have become worn or lost their alinement.

A further object of the invention is to provide simple means for disposing the work-holding and forming elements.

Another object of the invention is to attain a considerable saving in time and labor for the servicing of the machine along the lines mentioned.

With the above objects in view, and any others which may suggest themselves from the description to follow, a better understanding of the invention may be had by reference to the accompanying drawings, in which:—

Fig. 1 is a front elevation of a typical bending brake.

Fig. 2 is a cross-section on an enlarged scale, of that portion of the brake which immediately applies to the work.

Fig. 3 is a view similar to Fig. 2, showing the work-holding and forming elements improved in accordance with my invention;

Fig. 4 is a fragmental elevation, on an enlarged scale of a portion of the improved bending brake, broken away at different points to disclose various parts;

Fig. 5 is a similar view, showing a modification of the work-holding elements;

Fig. 6 is a cross-section, similar to Fig. 3, of the modified working elements after accomplishing a bending operation; and

Fig. 7 is a perspective view showing the work indicated in Fig. 6 before and after the said bending operation.

Referring specifically to the drawings, it is seen that the standard bending brake has its top bending leaf at 10, the upper jaw at 11, the edge bar of the upper jaw at 12, the lower bending leaf at 13, and the top edge bar for the same at 14. It is apparent that both the jaw 11 and the bending leaf 13 are cut down slightly to seat the respective edge bars, so that the screws 15 and 16 securing the same may not shear from the pressure of the bending operation.

Fig. 1 shows the screws 16 to be in a longitudinal series, and it is understood that the screws 15 are also in such a series.

The strain of the bending operations over an extended period of time shows in the dulling,

denting, and other deformation of the bar 12 in its beveled frontal edge. It is customary to remove this edge bar, replace it by a new one, and put the top bending leaf in a planing machine to trim the frontal edge of the edge bar in conformity with the angle of the jaw 11. This not only means the dismantling of the brake and its absence from service for some time, but it also makes the new installation of doubtful fitness or efficiency. Observation has shown that the strain on the edge bar 12 is suffered in places where the greatest stress is imposed during the bending operation. It is therefore inevitable that the holes in the edge bar for the screws 15 are deformed or elongated in one direction or another. When the new edge bar is applied, it is difficult to make its holes align with the directions which the screws have assumed from wear in the old holes. Also, the new bar may not align with the backing step for this reason, so that altogether the adjustment or adaptation of the new bar to the jaw becomes a formidable task in which the fitness or efficiency of the replacement is speculative.

A similar problem is presented by the top edge bar 14 of the lower bending leaf. This bar wears on its upper corner edge from pressure to bend the work, and a replacement meets the same conditions as above described. In fact, the work of replacing edge bars is made even more difficult by the fact that they are of high carbon steel and therefore difficult to alter or change.

It has been my intention to depart from the above conditions by providing replacements which are easily constructed and installed. Thus, referring to Fig. 3, it will be noted that the base 10a of the top bending leaf receives a separate jaw 17 underneath, this jaw serving as a frontal continuation of the leaf to the usual pointed edge.

The rear portion of the jaw 17 is reduced and seats in a L-shaped clamp 18 which is secured in a long recess 10b in the bottom face of the leaf base 10a by a series of bolts 19. It is understood that this joint protects the pressure of the jaw from shearing the bolts 19. The lower jaw 20 of the brake is in the present instance made and secured similarly to the other one as shown.

In the case of the lower leaf 13, I prefer to apply its edge bar 14 on the rear side. This construction has the advantage of presenting the upper corners of the carbon steel edge bar to the wear of the bending operations, where in the previous instance, wear would be suffered by the rear top edge of the apron itself. By making the edge bar 14 removable, it is not necessary to dismantle the lower bending leaf to renew its rear top edge.

In my construction, the edge bar 14 rests in step 13a formed on the rear side of the lower bending leaf and is secured by a clamping bar 21 fastened by bolts 22.

5 It will be evident that it is easy to remove the jaws 17 in case of wear by simply loosening the bolts 19, this also applying to the edge bar 14 by means of the bolts 22. The jaws and edge bar, by constituting the elements immediately engaging the work, can thus be handled apart from the machine itself. They may be re-conditioned if it is feasible; or, if this is impractical or not advisable, a new set of elements may be installed as replacements without keeping the machine out 15 of service any appreciable length of time.

In the replacing of the jaws 17, it is evident that no problem of wear or deformation at individual points is presented. The sturdy clamp 18 and securing bolts 19 form a firm receptacle and 20 fastening for the jaw, and there are therefore no difficulties in adjustment or the finding of ill-fitting places or conditions incompatible with the proper seating of the new jaw.

The facility in replacing the jaws and edge bars 25 of the improved type makes it possible to quickly change the jaws whenever desired, and these may be formed as dies to impart prescribed formations to the work when clamped or bent. With jaws of different die-formations available, it is an 30 easy matter to change the jaws for the work as specified.

It will be apparent from the above description that I have provided a set of work engaging and forming elements for the bending brake which 35 make for the saving of time and labor, and encourage the maintenance of these elements in the best possible condition for a high standard of efficiency.

While I have so far described the main embodiment of the invention, the same may be replaced where desired by the modified units shown in Figs. 5 and 6. Here it is seen that the jaws 17 and 20 are made in sections 17a and 20a of fractional length, these being shown spaced from 45 one another. The bar 14 is similarly divisible into sections 14a. As before, the clamps 18 and 21 may secure any number of these sections in line, and then may be spaced to afford clearance for portions of one or more pieces of work which 50 are not intended to be bent. Thus, the spaces between the sections afford room for the flanges

or wings of angle bars, channels and the like. With the sectional jaws positioned as in Fig. 3, an angle bar 25 may be laid with the flange 25a extending downwardly and severed at the site where the bar is to be bent. A quarter-turn bend 5 places the work in the position as indicated by dot-and-dash lines in Fig. 6, so as to appear as in Fig. 7.

It is thus apparent that by replacing the regular jaws with sectional ones, it is possible to insert one or more pieces of work with vertical flanges or portions in the brake, and to leave clearance for such flanges or bends while the work is being bent. The novel jaw installation is therefore of an interchangeable character and 15 capable of handling a greater variety of work.

I claim:—

1. In a bending brake including at least one bending leaf, a removable jaw for said leaf, said jaw having a rearwardly extending shank lapping 20 the forward edge of one surface of said leaf, an elongated clamp having a portion lapping substantially the entire rear edge of said jaw to hold the same against said leaf, said leaf having an elongated recess therein parallel to said rear edge 25 of said jaw, an elongated boss on said clamp fitting in said recess, and means extending through the floor of said recess and removably securing said boss in said recess whereby to clamp said jaw to said leaf and positively lock the same and said 30 clamp against rearward departure.

2. In a bending brake including at least one bending leaf, a removable jaw for said leaf, said jaw having a rearwardly extending shank lapping the forward edge of one surface of said leaf, 35 an elongated clamp having a portion lapping substantially the entire rear edge of said jaw to hold the same against said leaf, said leaf having an elongated recess therein parallel to said rear edge of said jaw, an elongated boss on said clamp fitting in said recess, said boss and recess extending substantially the entire length of said jaw, said boss and recess having abutting front and rear faces substantially perpendicular to the plane of said surface of said leaf, and means extending through the floor of said recess and detachably securing said boss in said recess, whereby to clamp said jaw to said leaf and positively lock the same and said clamp against rearward and forward departure.

THOMAS J. KELLEHER.
